UNITED STATES PATENT OFFICE.

RENALDO SOLANO, OF BROOKLYN, NEW YORK, ASSIGNOR OF TWO-THIRDS
TO JCHN W. HOWARD AND DAVID R. MORSE, BOTH OF SAME PLACE.

SIGNAL FOR RAILWAY-CARS.

SPECIFICATION forming part of Letters Patent No. 349,959, dated September 28, 1886.

Application filed September 23, 1885. Serial No. 178,336. (No model.)

To all whom it may concern:

Be it known that I, RENALDO SOLANO, late of San Francisco, in the State of California, but now of Brooklyn, in the county of Kings 5 and State of New York, have invented certain Improvements in Signals for Railway-Cars, of which the following is a specification.

This invention relates to that class of signal apparatus which is carried by the car, and the 10 principal object of which is to indicate when the car is in motion or at rest; and its object is to provide a simple, efficient, and easily-actuated apparatus for said purpose.

My invention comprises certain novel combinations of parts whereby this object is effectually secured.

Figure 1 is a side view, and Fig. 2 an end view, of an apparatus embracing my said invention. Figs. 3 to 7, inclusive, are detail 20 views, on a larger scale, of certain parts of said apparatus. Fig. 8 is a top and Fig. 9 is a side view illustrating the operation of my said invention in connection with an air-brake mechanism.

25 A indicates the car-body, and B the rear platform thereof. These may be of any ordinary or suitable construction, and, when desired, the car may be of the simple character and construction known as a "platform-car."

30 C is a cylinder provided with an internal piston and with a piston-rod, a. This cylinder, with its adjuncts, is attached to the car in the manner usual with the air-cylinders of the well-known air-brake, and the cylinder, its 35 piston, piston-rod, valves, and other adjuncts may be the same as those used with or in connection with the cylinders of air-brakes, and from a suitable source of supply the cylinder is supplied with compressed air in the manner usual with the cylinders of air-brakes. As such construction is well known and understood by mechanical engineers, railway mechanics, &c., it is not necessary to describe the same in detail here.

45 When desired, the usual air-brake apparatus may be adopted *in toto*, the piston-rod a being extended to connect the brake mechanism therewith, to enable the movement of the piston within the cylinder to actuate the brake 50 in the usual or well-known manner.

In the apparatus shown in the drawings a link or lever, D, is pivoted to the car-body at its upper end, and at its lower end to a rod, E, which connects to a horizontal crank-arm, b, on the lower end of the vertical signal standard, shaft, or journal F, which is supported in suitable bearings on the platform B, so that the said standard is capable of a movement about its own axis. This lever D, which gives movement to the signal, as hereinafter explained, may be connected with the brake mechanism in any suitable manner; but I prefer that shown in Figs. 8 and 9. The piston-rod a has at its outer end a cross-pin, a', which passes through a slot, b", in a lever, D', which, 65 like the cylinder, is secured to the car-body. One arm, a", of this lever D' is attached to a rod, b", which extends to a yoke, c", which, by a rod, d", and suitable brake-lever, e", and brake-rods f", actuates the brakes g" from the 70 piston aforesaid, the arrangement of the parts being such that when the brakes are applied to the wheels, as in stopping the car and as while the car is stopped, the movement of the signal-standard F will bring the signal to the 75 position which indicates that the car is slowing up or is stationary, and when the brakes are released from the wheels the same movement of mechanism which so releases them will turn said signal-standard to bring the 80 signal to the position which indicates that the car is started or in motion, or is (the brakes having been brought from the wheels) on the point of starting. From the opposite end of the lever D' may extend a rod, E", which connects with a lever corresponding to D' on the next or adjacent truck, to operate said lever from said rod in the same manner that the lever D' is operated from the piston-rod of the cylinder, as herein described.

The motion or the reverse of the car is in the usual railway practice accompanied by the release or application, as the case may be, of the brakes, and hence it follows that the signal apparatus, being actuated in unison with the 85 brakes, will correctly indicate, according to the circumstances, the motion or the stationary condition of the car.

As concerns the simultaneous operation of the signal and the brake mechanism in the ap- 90 95 100

paratus as represented in the drawings, movement is transmitted from the cylinder C as follows: The piston-rod a has a lateral stud or pin, c, which passes through a slot, f, in the link or lever D, so that the movement of the piston-rod in one direction or the other will communicate a corresponding movement to the rod E, and consequently to the crank-arm b.

10 Upon the upper end of the standard F is the lantern G, (shown in Figs. 4 and 5,) one face of which is provided with a single pane, a', and another, preferably one at right angles to that first mentioned, is provided with two 15 panes, b'. In lieu of this distinguishing difference between the two sides, any other—such as differences in color—may be adopted.

By actuating the cylinder mechanism, as with an air-brake, to move the piston-rod outward, the rod E, as shown in Fig. 1 and in the dark lines of Fig. 3, brings one of the faces aforesaid of the lantern to the rear, and by similarly giving a reverse movement to the piston-rod the rod E is moved backward, as 25 indicated in dotted outline in Fig. 3, to bring the other face to the rear, the signal being thus operated by a movement around or upon its own axis of its standard, shaft, or journal F, imparted from the compressed-air cylinder by 30 the piston and piston-rod through mechanism connecting the latter with said standard, shaft, or journal F. One of the faces of the lantern, when turned to the rear, being understood to indicate that the car is in motion, signals that

fact to those in the rear. The other face being 35 understood to indicate, when turned to the rear, that the car is at rest, knowledge of that fact is in like manner signaled to the rear.

When desired, a signal-disk of the ordinary or any suitable kind—as, for example, that 40 shown in face view in Fig. 6 and edge view in Fig. 7—may be substituted for the lantern with the same effect.

I do not confine myself to the employment of the special mechanical devices for connecting 45 the signal devices with the piston-rod, as various means of transmitting motion may be used in lieu of those herein set forth, so far as concerns the broad principle of my invention; but those herein set forth are those which in 50 my judgment are to be preferred in point of simplicity and directness and positiveness of action.

What I claim as my invention is—

In a railway-signal apparatus carried by or 55 on the car, the combination of a signal device, a standard, shaft, or journal constructed and arranged to receive an axial movement, a compressed-air cylinder, piston, and piston-rod, and mechanical devices for connecting the said standard, shaft, or journal with the piston-rod, substantially as and for the purpose herein set forth.

RENALDO SOLANO.
